Des. 238,957
Patented Feb. 24, 1976

238,957

CRIBBAGE BOARD

Chester H. Johnson, Maple Lake, Minn., assignor of a fractional part interest to Merchant, Gould, Smith & Edell, Professional Association, Minneapolis, Minn.

Filed Sept. 24, 1974, Ser. No. 508,737

Term of patent 14 years

Int. Cl. D21—01

U.S. Cl. D34—5 TT

FIG. 1

FIG. 2

FIG. 1 is a view in perspective showing the top, one end and one side of a cribbage board of my design; and

FIG. 2 is a view in perspective thereof showing the bottom and end and side opposite that shown in FIG. 1.

I claim:

The ornamental design for a cribbage board, substantially as shown.
